SURFACING MATERIAL

Carl W. Winkler, Clay Township, St. Joseph
County, Ind.

Application April 13, 1945, Serial No. 588,166

6 Claims. (Cl. 154—49)

1

This invention relates to surfacing material. It is sometimes desirable to provide a synthetic surface which will closely simulate the properties of a natural surface. For example, it may be desirable to provide a playing surface which possesses such properties that it permits a game to be played thereon under the same conditions presented by a natural playing surface. That is, the playing surface is to have the same "feel"; the same surface texture; and the same resilience and other properties which a natural surface, such as turf, possesses. Such playing surfaces may be used either in interior installations, or out-of-doors. In the latter case they must be waterproof and weather resistant; and their advantage may lie in reduction of upkeep costs.

One application of the invention is for use as a putting green for a golf course. Putting greens require constant care, as watering, rolling, fertilizing, seeding, weeding and cutting. The cost of such care is very high. Consequently, a surfacing material which possesses properties permitting golf to be played thereon in substantially the same manner as golf is played on a natural putting green, can be used to materially reduce maintenance and operating costs of golf courses.

The primary object of the invention is to provide a surfacing material possessing the properties and advantages mentioned above.

A further object is to provide a surfacing material for exterior use which will not deteriorate when subjected to changing weather conditions, which provides drainage for water, and which can be taken up during winter weather.

A further object is to provide a surfacing material of laminated character which will conform to any desired contour characteristic of a playing surface without wrinkling or curling or otherwise exhibiting properties not desired in a playing surface.

Other objects will be apparent from the description, drawing and appended claims.

In the drawing:

Fig. 1 is a perspective view illustrating the surfacing material applied to a golf putting green.

Fig. 2 is a sectional view illustrating the material installed, as in a golf course.

Fig. 3 is a fragmentary perspective view of the surfacing material.

Fig. 4 is a sectional view of a modified embodiment of the material.

Fig. 5 is a sectional view illustrating the manner in which sections of the material containing a golf cup are employed.

The invention is illustrated in the drawings as

2

applied to or used in a golf course to form the putting greens thereof. Numeral 10 of the drawing designates the surface of the ground at the approaches to a putting green 11 which is formed of our new surfacing material. At the space which the putting green occupies, the ground is dug to provide a shallow recess 12 to uniform depth at its margins and of desired contour or topography. The bottom of the recess is smoothed or leveled to form a firm foundation as by rolling. The bottom and side walls of the recess are treated, as by an oil or other material which prevents the growth of weeds at said surfaces. It is important, however, that adequate drainage be provided, and therefore the earth must not be packed too solidly or treated with any material of such character as to provide a continuous layer or surface at the surfaces of said recess which will prevent seepage of water therethrough. To facilitate drainage, especially at low ground, in clay soil, or in any location where drainage is poor, it may be desirable to provide a special base surface layer at recess 12, as a layer of gravel or mineral aggregate (not shown). In some cases, it may be necessary to use drainage tile (not shown) in the manner well understood by those versed in the art of drainage.

The surfacing material of which the golf green is formed is of laminated construction. 30 Its thickness is uniform and its size and shape corresponds to the recess 12 whereby it fits snugly therein, without cracks or crevices between its edges and the marginal surfaces of recess 12. Likewise its upper or playing surface must not 35 be bulged or wrinkled, and the margin of its upper surface must merge or be flush with the surface 10 of the playing area at all points therearound.

The bottom lamination or layer 13 of the surfacing material is preferably strong and durable. 40 Also, it is preferably sufficiently flexible or pliable to permit it to assume the contour of and to hug the bottom of recess 12 if the same is rolling or otherwise contoured in the manner and to the limited extent that golf greens are commonly contoured for the purpose of introducing the element of skill in putting thereon. Layer 13 will 45 preferably be approximately one inch in thickness, and that thickness will be uniform throughout. Layer 13 may be made of such materials as hard rubber; wool, cotton or cellulose matting impregnated with waterproofing material to 50 form a fairly solid body; plastic sheeting; alpha cellulose; waterproofed plywood; or the like. Selection of the material used in any instance

will be determined by the conditions of use at the locale of installation. It is preferable, however, that layer 13 shall not possess any substantial degree of resilience or compressibility.

A layer 14 is superimposed upon layer 13, and is preferably approximately one-half inch in thickness. This layer should possess the properties of resilience and compressibility, and should yield upon impact to act as a buffer without imparting any substantial rebound action to an object striking the same. At the same time it must resist permanent deformation or depression incident to strain, pressure or impress. Spongy material, such as sponge rubber or plastic sponge serves well for these properties, although any material characterized by myriad voids therethrough and by the properties of flexibility, limited resilience and shape or form retention or return may be used if suitably waterproofed.

Layer 15 is superimposed upon layer 14 and is preferably approximately one inch thick. Its properties are preferably similar to those of layer 14, though somewhat lesser in degree. In other words, limited resilience, compressibility and yieldingness are desirable. In order to provide these properties sponge rubber or sponge plastic having smaller voids and greater mass per cubic inch than is characteristic of the material forming layer 14 may be employed. Also, to further reduce or limit the properties of compressibility and yieldingness of sponge material, it may be provided with continuous skins of rubber or other flexible material at its opposite faces. Such skins may either be formed integrally with the sponge material by processes well known in the art of making sponge rubber, or may be separate layers adhered to the faces of the sponge material. Adherence of preformed facings may be preferable in cases where the surface skin or layer is required to be of a thickness which imparts substantial firmness and at least a measure of stiffness to layer 15. Alternatively, felted materials having requisite physical properties and waterproof character may be employed.

The top layer 16 of the surfacing material may be a rug material or matting which provides a "feel," texture and resistance to rolling of a golf ball thereon, which closely resembles close-cut grass. The material will preferably comprise a flexible firm woven or felted backing 17, and a nap 18 formed of flexible fibers projecting from $\frac{3}{8}$ " to $\frac{5}{8}$ " above the backing. The backing and the fibers will be suitably waterproofed, as by impregnation of the backing and coating of the fibers (without adherence of the fibers in bunches) by flexible plastic material or by rubber. Alternatively, the fibers themselves may be inherently water resistant or waterproof. The nap 18 will preferably be colored to simulate the appearance of grass.

The various layers or laminations 13, 14, 15 and 16 above described may be secured together to form a unitary material; or layers 13 and 14 may be secured together to form a base unit and layers 15 and 16 may be secured together to form a surface unit. Suitable waterproof adhesives, of which different types, such as rubber cement, are available, may be employed to firmly adhere or secure the layers in face engagement. This securing of the layers insures against displacement, curling and other undesirable action or movement of the material and the individual layers thereof. Where the material is adhered to form two separate units or sections, such as a base unit

and a surface unit, the base unit may be fabricated in small sections of such size that they may be easily handled. This facilitates removal, storage and replacement as is desirable in latitudes where the ground freezes during the winter. The surface unit is preferably unitary in such case, but is made of materials which can be rolled, thereby facilitating handling and storage.

The two unit make-up of the material requires the provision of means to secure the layers together. One form of such means is illustrated in Fig. 4 and consists of brads or other fasteners 19 having small heads 20 which are driven or otherwise forced into the back 17 of layer 16 to an extent sufficient to insure against contact therewith by a golf ball which has been pitched or lofted onto the green. The shank of the brads or fasteners 19 will be of a length sufficient to pass through layer 15 and penetrate and anchor into layer 14, and will preferably terminate above bottom layer 13. Consequently, the fasteners can move bodily with the surfacing material as layers 14 and 15 are compressed or caused to yield upon impact. In this way, although the fasteners are rigid, they do not adversely affect or destroy the uniformity of the action or "give" of the surfacing material nor provide "hard spots" therein. The shanks of the brads may be barbed for secure anchorage with the layer 14 if desired, but such barbs should accommodate separation of the two units without excessive tearing of or injury to the layer 14.

Suitable provisions for drainage must be made to avoid water retention or waterlogging of the surfacing material during and following rainy weather. For this purpose, layer 15 may be provided with a multiplicity of substantially equi-spaced passages 21 therethrough. These passages should be of the smallest diameter which will permit water to drain therethrough, in order that the uniformity of the surfacing material and of its properties will be maintained. A multiplicity of substantially equi-spaced aligned passages 22 may be formed in the lower layers 13 and 14. These passages will preferably extend at an angle and may be somewhat larger in diameter than passages 21. Also, if desirable, wicks 23 of any suitable material may be mounted in passages 22 to facilitate or improve drainage.

It is common practice in the maintaining of golf courses to change the location of the cup 24 in the green from time to time. This practice serves to avoid excessive wear or play at any particular part of the green and also to slightly change the conditions of play and to increase the skill required of the player. The same practice can be used with greens formed of this surfacing material. An illustrative construction which accommodates this practice is illustrated in Fig. 5 and includes the provision in the surfacing material of a plurality of openings of the same size and shape. Each of said openings receives a laminated section 25 formed of the same materials of which the surfacing material is formed with a snug fit in a manner to provide a continuous overall upper playing surface. The laminations of each section 25 are adhered together so that said sections are removable as a unit. One section 25 may have the cup 24 imbedded centrally therein and permanently connected thereto.

As an alternative to the above construction, the openings and the sections 25 may be formed of the same size and shape as the cup 24, so that the cup 24 and sections 25 are interchangeable. Except for their smaller size, sections 25 of this

alternative embodiment will be of the same construction and will fit in and be removable from the openings in the surfacing material in the same manner above described.

The use of the surfacing material out-of-doors, mounted directly in and upon the ground as above described for the purpose of providing a synthetic golf green, faithfully reproducing the properties and characteristics of a natural golf green, is only one application of the invention. Other applications which may be suggested are indoor golf practice greens, and indoor and outdoor playing areas for lawn tennis, badminton and other games. Also, the material may be used in other relations, such as for floor coverings in cases or locations which require durability, strength, resilience or sound deadening or eliminating properties. In each such application, the properties desired will determine the materials selected for the different layers or laminations, in the same manner mentioned above with reference to selection of such layers for use as a golf green.

The surfacing material will wear well because of its yielding properties. It can be colored to give any desired appearance, design or decorative effect. The securing of the layers will hold the material against wrinkling, curling or other undesired displacement. Also, except for cleaning in such installation as require it, the material does not require attention or upkeep as is required for natural playing surfaces, and hence will be economical for many applications where the cost of upkeep is high.

We claim:

1. Surfacing material comprising a firm flexible mat having a short uniform nap, a thick mat-supporting lamination of firm sponge rubber characterized by limited compressibility and resilience, a comparatively thin intermediate resilient cushioning lamination of sponge rubber of lesser density and greater compressibility than said mat-supporting lamination, a firm strong base lamination having limited flexibility and negligible compressibility, and means for securing said mat and laminations in superimposed continuous face contacting engagement, said laminations each having a plurality of drainage passages therein communicating with passages in adjacent laminations, the passages in the upper lamination having a cross-sectional size sufficient to permit drainage but insufficient to materially alter the reaction of the lamination to impact.

2. Surfacing material comprising a firm flexible mat having a short uniform nap, a thick mat-supporting lamination of firm sponge rubber characterized by limited compressibility and resilience, a comparatively thin intermediate resilient cushioning lamination of sponge rubber of lesser density and greater compressibility than said mat-supporting lamination, a firm strong base lamination having limited flexibility and negligible compressibility, and means for securing said mat and laminations in superimposed continuous face contacting engagement, said laminations each having a plurality of drainage passages therein communicating with passages in adjacent laminations, the passages in the upper lamination having a cross-sectional size sufficient to permit drainage but insufficient to materially alter the reaction of the lamination to impact, and wicks extending through the passages in said intermediate and base laminations.

3. Surfacing material comprising a firm flex-

ible mat having a short uniform nap, a thick mat-supporting lamination of firm sponge rubber characterized by limited compressibility and resilience, a comparatively thin intermediate resilient cushioning lamination of sponge rubber of lesser density and greater compressibility than said mat-supporting lamination, a firm strong base lamination having limited flexibility and negligible compressibility, and means for securing said mat and laminations in superimposed continuous face contacting engagement, said laminations each having a plurality of drainage passages therein communicating with passages in adjacent laminations, the passages in the upper lamination having a cross-sectional size sufficient to permit drainage but insufficient to materially alter the reaction of the lamination to impact, said upper mat-supporting lamination having a firm flexible resilient upper rubber web in bonded relation thereto and engaging said mat.

4. Surfacing material comprising a firm flexible mat having a short uniform nap, a thick mat-supporting lamination of firm sponge rubber characterized by limited compressibility and resilience, a comparatively thin intermediate resilient cushioning lamination of sponge rubber of lesser density and greater compressibility than said mat-supporting lamination, a firm strong base lamination having limited flexibility and negligible compressibility, and means for securing said mat and laminations in superimposed continuous face contacting engagement, said laminations each having a plurality of drainage passages therein communicating with passages in adjacent laminations, the passages in the upper lamination having a cross-sectional size sufficient to permit drainage but insufficient to materially alter the reaction of the lamination to impact, said base lamination being formed of non-cellular rubber.

5. Surfacing material comprising a firm flexible mat having a short uniform nap, a thick mat-supporting lamination of firm sponge rubber characterized by limited compressibility and resilience, a comparatively thin intermediate resilient cushioning lamination of sponge rubber of lesser density and greater compressibility than said mat-supporting lamination, a firm strong base lamination having limited flexibility and negligible compressibility, and means for securing said mat and laminations in superimposed continuous face contacting engagement, said laminations each having a plurality of drainage passages therein communicating with passages in adjacent laminations, the passages in the upper lamination having a cross-sectional size sufficient to permit drainage but insufficient to materially alter the reaction of the lamination to impact, said base and intermediate laminations being bonded together to form a preformed unit, and said mat and first named lamination being bonded to form a second preformed unit, said units being secured in superimposed relation by said securing means.

6. Surfacing material comprising a firm flexible mat having a short uniform nap, a thick mat-supporting lamination of firm sponge rubber characterized by limited compressibility and resilience, a comparatively thin intermediate resilient cushioning lamination of sponge rubber of lesser density and greater compressibility than said mat-supporting lamination, a firm strong base lamination having limited flexibility and negligible compressibility, and means for securing said mat and laminations in superimposed continuous face con-

tacting engagement, said laminations each having a plurality of drainage passages therein communicating with passages in adjacent laminations, the passages in the upper lamination having a cross-sectional size sufficient to permit drainage but insufficient to materially alter the reaction to impact, said securing means constituting brads extending through said mat and upper lamination and terminating within the body of said intermediate lamination.
